(57) **CLAIM**

I claim the ornamental design for a rounded platform tree stand, as shown and described.

DESCRIPTION

FIG. 1 is a top front perspective view of a rounded platform tree stand showing my new design;

FIG. 2 is a front elevation view thereof;

FIG. 3 is a rear elevation view thereof;

FIG. 4 is a right side elevation view thereof;

FIG. 5 is a top plan view thereof; and,

FIG. 6 is a bottom plan view thereof.

The broken lines showing a ladder is for illustrative purposes only and form no part of the claimed design.
